TOILET VENTILATOR

Ellis D. Greene, Rochester, N. Y.

Application May 7, 1937, Serial No. 141,283

1 Claim. (Cl. 4-213)

This invention relates to toilet ventilators and has for its principal object to provide a simple and efficient ventilating system of inexpensive construction for toilet bowls with which all odors from the toilet bowl are effectively evacuated especially during its use in order to prevent the escape of such odors into the toilet room thereby eliminating the annoyance and unhealthfulness incidental to the use of toilets in the house.

10 Another object of this invention is to provide a ventilating system that is easy and inexpensive to install.

15 A further object of this invention is to provide the intake of the ventilating system with a simple and easy mode of attachment to the bowl of the closet.

20 This and other objects and attendant advantages of this invention will become more readily apparent from the detailed description thereof which follows, reference being had to the accompanying drawing in which

Figure 1 is a front elevation of a water closet equipped with my novel ventilating system.

Figure 2 is a side elevation thereof.

25 Figure 3 is a detail sectional view of a modified form of ventilating fan and its connection for use with the ventilating system.

Figure 4 is a partial top plan view of the water closet bowl with the ventilating system mounted thereon.

30 Figure 5 is an enlarged detail sectional view of the rear portion of the water closet bowl and the ventilating system attached thereto.

Figure 6 is a horizontal section of the intake 35 manifold of the ventilating system including its means for attachment to the water closet bowl.

Figure 7 is an enlarged vertical sectional view 40 of a water closet bowl in which the intake manifold for the ventilating system is embodied in the bowl proper.

In the several figures of the drawing like reference numerals indicate like parts.

The ventilating system forming the subject matter of this invention is illustrated in the 45 drawing as applied to a water closet having the bowl 1, a seat 2 on top of the bowl and a cover 3 extending over the opening in the seat. The seat and the cover are hingedly mounted at the back of the bowl on the horizontal pivot shaft 4 which 50 is supported by the spaced bolts 5, 5 which are suitably anchored in the top of the rear of the bowl 1. At the back of the bowl is located the water tank 6, and the pipe 7 connects the bottom of this water tank with the bowl for flushing 55 purposes. A suitable handle 8 on the outside of

the tank controls the flow of the water from the tank. The construction of the water closet so far described may be any one of this type of closets now in use and my ventilating system is constructed so as to be readily and easily applicable to all of them to prevent the escape of 5 unpleasant and harmful odors during the use of the closet.

This ventilating system is inexpensive to install and comprises the air intake manifold 10 10 which is formed up of sheet metal in the form of a substantially narrow flat tube which is closed at one end and has its other end terminate into a tubular extension 11 of cylindrical cross section. One side of the manifold is provided with 15 the elongated inlet 12 thru which the air is drawn from the inside of the bowl as will hereinafter be described. The other side of the intake manifold 10 is provided with the mounting flange 13 which is suitably fastened to the anchoring bar 20 14. The latter is provided with a pair of vertical holes 5A, 5A which are spaced so as to correspond with the spacing of the bolts 5, 5 on the top of the rear of the bowl. In this way the bolts 5, 5 are adapted to pass thru the anchoring bar 25 14 to have the nuts 15 clamp the anchoring bar to the top of the back of the bowl below the hinge of the seat and the cover thereof.

With the anchoring bar 14 fastened in place in the manner above described, the intake manifold is held supported so as to project from the outside of the bowl over the edge thereof and extend over the inside along the rear of the bowl between it and the rear of the seat 2. The inlet 30 12 is thus located over the inside of the bowl substantially the full length of the rear thereof to provide a large intake opening for a quick and effective evacuation of the air within the bowl.

35 The intake manifold is connected to a suitable exhaust fan which is operated by an electric 40 motor that is controlled by a switch which is preferably operated by the cover of the closet bowl. For this purpose a pipe line 16 is connected to the cylindrically tubular open end of the intake manifold 10, which pipe line leads to 45 the exhaust fan 17 and from the exhaust fan to any point where the odor of the evacuated air will not be objectionable. Such a point may be the roof of the house or the soil pipe of the sewer system etc.

50 In the form of exhaust fan 17 illustrated in Figure 1 the air enters the center of its circular casing and is forced out by the blades tangentially to the circular outer wall thereof. In the form of exhaust fan 17A illustrated in Figure 3, the fan 55

is mounted in a cylindrical housing 18 which has a conically reduced inlet 19 and a similar outlet 20 for connection with the pipe line 16. If enough natural draft is present in the pipe line 16 for the evacuation of the air from the closet bowl, an exhaust fan may be dispensed with and a suitable length of pipe line is then used to take the place of the fan casing.

The exhaust fan is electrically driven and to make the operation of the fan most effective it is controlled by a switch that is automatically operated by the cover 3 of the closet bowl. When this cover is raised to uncover the opening in the seat just prior to the use of the closet, the fan is started to exhaust the air from the bowl while the closet is being used and kept on operating until the cover is closed over the seat after the closet has been used. This makes certain that all of the foul air is withdrawn from the bowl before the exhaust fan is stopped. Of course some ventilation continually takes place even after the exhaust fan has stopped because of the natural draft in the pipe line.

For the automatic operation of the fan a switch 21 is mounted on top of a bracket 22 which is supported from the anchoring bar 14 so as to locate the switch in a position in which the projecting push rod 23 of the switch is contacted by the cover when the cover is swung open to rest against the tank of the closet. The push rod 23 is spring pressed and when the cover makes contact with it, it is forced into the switch housing to have the contact member 24 close the electric motor circuit between the terminal contacts 25 and 26. With the cover open and leaning against the water tank, the electric circuit of the fan motor is thus held closed so as to continually operate the fan.

As soon, however, as the cover is being closed over the closet seat and swung away from the

tank, the push rod 23 is released by the cover and moves out of the switch casing to cause the connecting member 24 to open the electric circuit between the terminal contacts 25 and 26 and thus stop the fan.

In Figure 7 I have illustrated the intake for the ventilating system embodied in the bowl construction proper. In this construction the manifold 27 is cast into the bowl as an integral part thereof so as to have its mouth 28 on the inside wall 10 below the top of the bowl. An opening 29, which may be slightly tapered, leads into the intake manifold from the outside of the bowl and is adapted to have the end 30 of the pipe line 16 extend thereinto for connection therewith.

I claim:

A ventilating system for closets comprising in combination a bowl, a seat, a cover over the seat, anchoring bolts projecting from the top of the back of the bowl, said bolts carrying a hinge element secured to the cover to cause said cover to swing on said bolts, an intake manifold supported on said bowl by said anchoring bolts, a pipe line connected to said intake manifold, an exhaust fan connected to said pipe line, an electric motor for operating said exhaust fan, a switch for controlling the operation of said electric motor, a bracket carried by said manifold for supporting said switch above and to the rear of the cover of said closet in cooperative relationship with said hinge element so as to determine precise contact between the cover and said switch for the operation of the exhaust fan when said cover is swung into a substantially vertical position in preparing the closet for use and operate the switch to stop the operation of the exhaust fan when placing the cover over the seat of the bowl after the use of the closet.
